Primary Examiner — Cynthia Ramirez(74) *Attorney, Agent, or Firm* — Montgomery Patent & Design; Robert C. Montgomery**CLAIM**

The ornamental design for a pull cart for skis and accessories, as shown and described.

DESCRIPTION

FIG. 1 is an isometric view of a pull cart for skis and accessories;

FIG. 2 is a front view thereof;

FIG. 3 is rear view thereof;

FIG. 4 is a left hand side view thereof;

FIG. 5 is a right hand side view thereof;

FIG. 6 is a top view thereof;

FIG. 7 is a bottom view thereof;

FIG. 8 is an isometric view of a pull cart for skis and accessories with a cover removed for illustration;

FIG. 9 is a front view thereof;

FIG. 10 is a rear view thereof;

FIG. 11 is a left hand side view thereof;

FIG. 12 is a right hand side view thereof;

FIG. 13 is a top view thereof;

FIG. 14 is a bottom view thereof; and,

FIG. 15 is an isometric view of a pull cart for skis and accessories with containment barrels in a collapsed position for illustration.

The cross-hatching shading added to the cover surface in FIGS. 1 through 7 is fragmentarily shown for convenience of illustration; it being understood that the cross-hatching is uniformly continued over the surface on which it appears.
